The ornamental design for a front bumper for a vehicle, as shown and described.

Jul. 11, 2017 (DE) 40 2017 100 810

DESCRIPTION

(51) **LOC (11) Cl.** **12-16**

This application contains subject matter related to the following co-pending U.S. design patent applications:
Application Ser. No. 29/631,774, filed herewith and entitled “Vehicle, Toy, and/or Replicas Thereof”; and
Application Ser. No. 29/631,782, filed herewith and entitled “Front Bumper for a Vehicle”.

(52) **U.S. Cl.**

FIG. 1 is a front view of a front bumper for a vehicle according to the design;

USPC **D12/169**

FIG. 2 is a right, front perspective view thereof;

(58) **Field of Classification Search**

FIG. 3 is a left, bottom perspective view thereof;

USPC D12/169, 102, 113, 115, 117, 120;

FIG. 4 is a right side view thereof;

296/180.1, 180.2

FIG. 5 is a left side view thereof;

CPC B60R 19/02; B60R 19/04; B62D 25/08

FIG. 6 is a top view thereof;

See application file for complete search history.

FIG. 7 is a bottom view thereof; and,

(56) **References Cited**

FIG. 8 is a rear view thereof.
